J. A. KUENZ

TOY

Filed May 20, 1922

INVENTOR.
Joseph A. Kuenz

BY

Chappell & Carl

ATTORNEY\$

UNITED STATES PATENT OFFICE.

JOSEPH A. KUENZ, OF JACKSON, MICHIGAN.

TOY.

Application filed May 20, 1922. Serial No. 562,368.

To all whom it may concern:

Be it known that I, JOSEPH A. KUENZ, a citizen of the United States, residing at the city and county of Jackson, State of Michigan, have invented certain new and useful Improvements in Toys, of which the following is a specification.

This invention relates to improvements in toys.

10 The main object of this invention is to provide an improved toy having a plurality of figures with movable parts which is very simple and economical in structure and may be operated by very small children.

15 Further objects, and objects relating to structural details, will definitely appear from the detailed description to follow.

I accomplish the objects of my invention by the devices and means described in the 20 following specification. The invention is clearly defined and pointed out in the claim.

25 A structure which is a preferred embodiment of my invention is clearly illustrated in the accompanying drawing, forming a part of this application, in which:

Fig. I is a plan view of my improved toy, a portion of the figures being shown by dotted lines only.

30 Fig. II is an enlarged view partially in vertical section on a line corresponding to line 2-2 of Fig. I.

Fig. III is a detail section through one of the figures on a line corresponding to line 3-3 of Fig. I.

35 Fig. IV is a plan view of one of the blanks from which the head is formed.

Fig. V is a plan view of one of the body blanks.

In the drawing similar reference characters refer to similar parts throughout the 40 several views and the sectional views are taken looking in the direction of the little arrows at the ends of the section lines.

Referring to the drawing, the figures illustrated 45 represent chickens, although these may be varied, as desired.

My improved toy comprises a supporting plate 1 provided for convenience in manipulation with a handle 2. This supporting plate has annularly disposed holes 3 therein. The body members 4 are mounted in an annular groove, those of the structure illustrated being radially disposed and positioned above the holes 3. The heads 5 of 55 these figures are pivoted at 6, the pivots

being positioned so that the heads fall or drop to the plate by gravity. I provide a counterweight 7 of such size or weight as to counterbalance all of the heads. The weight is connected to the heads at the rear of their pivots by cords 8 passed through the holes 3, so that the heads are held normally erect by the weight, but when the weight is swung to loosen the cords the heads fall to the plate. 65

By imparting a circular swinging movement to the weight the cords are successively released, thereby permitting the heads to drop successively causing a "picking" movement of the heads, the heads striking 70 the plate successively and producing a tapping sound.

The figures 4 represent chickens, but various forms of figures with movable parts may be used and also they may be variously 75 positioned.

In the embodiment illustrated the bodies 4 are formed of sheet metal stampings 9, shown in the flat in Fig. V. These stampings have projecting tongues 10 at the edges thereof. The stampings are suitably conformed and brought together in pairs with the tongues 10 in opposed relation, the washers or perforated coupling members 11 being arranged over the coacting pairs of 80 tongues and secured by folding the tongues down upon the same. The heads 5 are similarly formed of stampings 12 provided with tongues 10 corresponding to those of the body. The head members 12 are provided 85 with holes 13 to receive the pivots 14 formed integrally with the body members,—see Fig. V. The parts thus formed are very economical to produce and assemble. 90

Having thus described my invention, what 95 I claim as new and desire to secure by Letters Patent, is:

In a toy, the combination of a body comprising a pair of complementary sheet metal stampings disposed edge to edge and having outwardly projecting tongues on the edges thereof, the tongues of the members being side by side when the members are in assembled relation, and perforated coupling members arranged over the coacting pairs 100 of tongues, the outer ends of said tongues being folded over said coupling members. 105

In witness whereof, I have hereunto set my hand and seal.

JOSEPH A. KUENZ. [L.S.]
